UNITED STATES PATENT OFFICE.

THADEUS KEITH, OF NEW YORK, N. Y.

BURIAL APPARATUS.

1,028,735.

Specification of Letters Patent.

Patented June 4, 1912.

Application filed July 31, 1911. Serial No. 641,474.

To all whom it may concern:

Be it known that I, THADEUS KEITH, a citizen of the United States, residing at New York, in the county of New York and

5 State of New York, have invented certain new and useful Improvements in Burial Apparatus, of which the following is a specification, reference being had therein to the accompanying drawing.

10 This invention relates to burial apparatus and has for its object to provide an improved burial apparatus by means of which a coffin may be easily and effectively handled at the grave and lowered into the 15 same.

The invention consists in a burial apparatus and in details thereof constructed and arranged as hereinafter set forth and claimed.

20 Referring to the accompanying drawings: Figure 1 is a side view of a burial apparatus constructed in accordance with this invention and showing it in position for lowering a coffin into a grave. Fig. 2 is a plan view of the apparatus. Fig. 3 is a longitudinal section of the apparatus located over a grave. Fig. 4 is an end view in cross section of the apparatus located over a grave. Fig. 5 is an enlarged detail 30 view in perspective of a portion of the apparatus in which a coffin is suspended. Fig. 6 is an enlarged detail view with parts broken away and in section showing one of the supporting bars for a coffin. Fig. 7 is 35 an enlarged detail view in perspective of a portion of one of the uprights and a weight and cord employed therewith.

In carrying out the invention an elevated frame is provided which is adapted to be 40 located over a grave, and, as here shown, preferably consisting of the slightly inclined pairs of uprights 1 located at the ends of the elevated framework and connected by pairs of longitudinal bars 2 and 45 3 and intervening longitudinally inclined brace bars 4, the pairs of uprights 1 being connected together by cross bars 5. Located at each end of the framework between the longitudinal bars 2 is a platform 50 6 supported on cross bars 7 mounted in the longitudinal bars 2, one of the platforms 6 being provided with sets of rollers 8 which enables a coffin placed upon the platform 6 to be pushed forward on to the same and 55 also off of the same to the middle of the frame work as hereinafter set forth. For ornamental purposes the cross 9 is mounted in the center of the framework upon the cross bar 10 connected to the longitudinal bars 3.

60 Located between the platforms 6 are transverse bars 11 on which a coffin is adapted to rest, as shown in Fig. 2, said bars being hinged at one end by means of a hinge 12 to one of the longitudinal bars 65 2 and secured at its other end to the other longitudinal bar 2 by a spring actuated locking pin 13. The coffin 14 is placed upon the platform 6 and rolled on to and off of the same by means of rollers 8 and 70 is moved to the position shown in Fig. 2 on the transverse bars 11. In order to move the coffin and lower it into the grave an apparatus is provided consisting of an iron bar 15 formed with an eye 16 at each end 75 and in conjunction with the rod 15 is a rod 17 having curved ends 18. A chain 19 is connected with each eye 16 of the rod 15 and has at its other end a ring 20 which is slid over the curved end 18 of the rod 17, 80 the curved end 18 preventing the ring 20 from accidentally slipping off of the end of the rod 17. A pair of chains 21 are employed in connection with the rods 15 and 17, one end of said chains 17 being connected by a link 22 with the rods 15 and 17 respectively, and the other end of said chains being connected with a cross rod 23 to which is connected one end of a hoisting rope 24 which passes over a roller 25 in the 90 center of the cross bar 10 and extends beneath the same to one end 26 thereof and downward to a windlass 27 mounted on one of the longitudinal rods 2. The windlass 27 is operated by a toothed wheel 28 95 on one end thereof which meshes with a pinion 29 on a shaft projecting from the longitudinal bar 2 and provided with a crank handle 30. Connected to rings 31, which in turn are connected to rings 32, 100 one of which is connected with an eye 16 and the other with the rod 17, are cords 33 which extend up through diagonal hollow rods 34 secured at the lower end to longitudinal bars 3 and at the upper end to the 105 upper end of the apparatus 1, the cord 33 passing over a pulley 35 in the top of the uprights 1 and down through a groove 36 in the upright 1 and having connected to its lower end a weight 37 slideable in the 110 groove 36. Secured to each of the cords 33 adjacent to the weight 37 is a flag 38. The

coffin 14, as shown in Figs. 2, 3, and 4, is in position to be lowered into a grave 39.

The operation of the apparatus is as follows: The elevated framework having been placed over a grave 39, the coffin 14 is pushed on to the platform 6 provided with rollers and from thence on the transverse bars 10. The chains 19 are then passed about the coffin and a ring 20 is slipped over each end of the rod 17, the rings 33 having been already slipped onto the rod 17. The transverse bars 11 are then released by turning back the pins 13 and swung downward out of the way and the coffin is lowered into the grave by unwinding the windlass 27. As the coffin is lowered into the grave the cords 33 draw the weights 37 upward on the uprights 1 to the top thereof and the flags 38 being carried up therewith are displayed and indicate that the coffin has been lowered to the bottom of the grave. The rings 20 and 33 are then pushed off of the rod 17 and the chains 19 and the rods 15 and 17 drawn up out of the grave by means of the hoisting rope 24.

It will be seen that by means of the apparatus hereinbefore described that a coffin may be readily and effectively handled by one or two persons and lowered into a grave.

What I claim is:

1. A burial apparatus comprising an elevated frame-work, a pair of bars adapted to lie parallel to a coffin, chains connected with one of said bars and detachably connected to the other bar, and adapted to be passed under a coffin, hoisting chains connected to said bars, and a hoisting mechanism on said frame work connected with said hoisting chains.

2. A burial apparatus comprising an elevated frame-work, a rod having a chain connected to each end adapted to extend

about a coffin, a second rod with which 45 said chains are detachably connected said rods arranged to lie parallel to the length of a coffin, hoisting chains connected to said rods, a hoisting rope mounted on said framework, and a windlass and operating mechanism connected therewith and mounted on said frame work.

3. A burial apparatus comprising an elevated frame-work, ropes and chains adapted to be secured to a coffin for suspending 55 the same, and hoisting mechanism connected with said ropes and chains, cords mounted on said elevated frame-work and connected with said rods, a windlass connected with said cords and weights 60 slideable upon said uprights having said cords secured thereto.

4. A burial apparatus comprising an elevated frame-work having longitudinal rods, a pair of rods and chains connected to said rods and adapted to be extended beneath the coffin, hoisting chains connected with said rods, a hoisting mechanism connected with said hoisting chains, hollow bars extending from the lower part of the frame-work to the top of the framework at its ends, grooved uprights at the ends of the frame connected at their upper ends to the upper ends of said hollow bars, pulleys at the upper end of said grooved uprights, 75 cords extending through said hollow bars, and through said grooved uprights and over said pulleys and connected at one end to said rods for securing a coffin, and weights connected at the other ends of said 80 cords and slideable in said grooved uprights.

In testimony whereof I hereunto affix my signature in presence of two witnesses.

THADEUS KEITH.
